UNITED STATES PATENT OFFICE.

FREDERICK SARGENT, OF CHICAGO, ILLINOIS.

EXPANSION CONNECTION.

1,342,133.

Specification of Letters Patent. Patented June 1, 1920.

Application filed October 20, 1914, Serial No. 867,628. Renewed September 22, 1917. Serial No. 192,827.

To all whom it may concern:

Be it known that I, FREDERICK SARGENT, a citizen of the United States, residing at Chicago, in the county of Cook and State 5 of Illinois, have invented certain new and useful Improvements in Expansion Connections, of which the following is a description.

My invention relates to means for connecting the tubes of surface condensers or other devices to the heads or other fixed portions 10 of the device.

The object of my invention is to provide a simple, reliable, durable and comparatively inexpensive device of the kind described adapted to prevent the possibility of leakage under substantially any conditions of temperature or service.

To this end my invention consists in the 20 novel construction, arrangement and combination of parts herein shown and described and more particularly pointed out in the claims.

In the accompanying drawings wherein 25 like or similar reference characters indicate like or corresponding parts:

Figure 1 is a side elevation of a surface condenser equipped with my improved connections with parts removed and broken 30 away to more clearly show the construction.

Fig. 2 is a longitudinal section of my improved connection and associated parts.

Fig. 3 is a view similar to Fig. 2 showing 35 a slightly modified construction of my connection.

In the drawings for the purpose of illustration my device is shown in connection with a surface condenser for forming a fluid tight flexible connection between the heads 40 of the condenser and the tubes.

As shown 1 is the condenser shell of the usual or any preferred form or construction provided with suitable heads or tube sheets 2-2 near each end adapted to jointly receive and support the tubes 3-3 between them in substantially the usual manner.

My improvement consists of means for securing the ends of the several tubes to the heads or tube sheets to form a fluid tight 50 connection between them and allow the free expansion of the tubes in relation to the heads. For this purpose my improved expansion connection may be employed at one end only of a tube, the opposite end of the 55 tube being expanded into or otherwise rigidly attached to the head, or my improved

connections may be provided at both ends of each tube. In either case my improved connection is provided to take the place of the usual soft metal, fibrous wooden or 60 other well known and unsatisfactory joints arranged to permit a slippage between the tubes or other expansible members and the heads or other fixed part of a device. As shown each opening for a tube in the heads 2 65 is provided with a shoulder 4 intermediate its ends and the inner portion 5 of each opening is formed to snugly fit the tube co-operating with it while the outer portion 6 is considerably larger with suitable screw 70 threads formed in its wall adapted to co-operate with an externally threaded sleeve 7.

The sleeve 7 is preferably bored slightly larger than the tube 3 and the inner end of the member 10 is soldered or otherwise 75 secured within the sleeve to form a fluid tight joint between the head and member. As shown the outer end of the sleeve 7 is provided with suitable notches 8 or other convenient means for engaging the sleeve 80 to screw the same into the part 6 of the opening. The part 10 is provided with a lateral flange 9 at its inner end adapted to be engaged between the inner end of the sleeve 7 and the face of the shoulder 4 to 85 form a conveniently detachable fluid tight joint between the extensible member 10 and the head. The outer end of the member 10 is rigidly secured to the projecting end of the tube 3 as at 11 by soldering, welding or 90 other convenient means adapted to permanently attach the member to the tube and form a fluid tight connection between them.

Any suitable means may be provided to secure longitudinal flexibility for the member 10. In the form shown the tube 3 projects slightly beyond the outer end of the sleeve 7 and the part of the member 10 outside the sleeve 7 is provided with a plurality of transverse corrugations 12 extending 100 from the outer end of the sleeve substantially to the connection 11. The length of the corrugated portion 12 depends in each case upon the amount of movement desired or necessary between the tube and the head 2. 105

In the form shown in Fig. 3 the sleeve 14 is preferably slightly larger in diameter than in the previously described form and its internal diameter is of sufficient size to receive and inclose the corrugated portion 110 17 of the longitudinally extensible member 18. The head 15 and shoulder 16 remain

substantially as hereinbefore described. In this form however the tube 19 may be made considerably shorter or if desired, the corrugated portion 17 of the extensible member 5 may be increased in length, in each form however the operation is very similar to the form hereinbefore described and an absolutely fluid tight flexible and expansible joint is provided adapted to provide for any 10 amount of expansion between the head of the tube, thus doing away with the difficulties encountered in surface condensers and other devices wherein the several parts are subject to considerable expansion or 15 where the expansion of the parts is not uniform thus causing straining and leakage.

Having thus described my improvement it is obvious that various immaterial modifications may be made in my device without 20 departing from the spirit of my invention, hence I do not wish to be understood as limiting myself to the exact form or construction shown.

What I claim as new and desire to secure 25 by Letters Patent is:

1. In a device of the kind described, a plate having a shouldered opening, and a tube extending into said opening, in combination with a longitudinally flexible member 30 having one end permanently attached to said tube adjacent the end thereof and substantially constituting a unitary structure, said member having its other end extended into said opening, and means for connecting said last mentioned end of said member to the wall of said opening to form a fluid 35 tight joint between said plate and tube.

2. In a device of the kind described, a plate having an opening and a tube extending 40 into and through said opening, in combination with a longitudinally flexible member having one end permanently attached to said tube adjacent the end thereof to substantially provide a unitary structure and 45 having its opposite end extended into said opening, and means for connecting said last mentioned end of said member to the walls of said opening to form a fluid tight joint between said plate and tube.

50 3. In a device of the kind described, a plate having a shouldered opening and a tube extending into said opening, in combination with a longitudinally flexible member having one end permanently attached to

said tube to substantially provide a unitary 55 structure and provided with a flange at its opposite end positioned in said opening and overlying said shoulder and means for clamping said flange against the shoulder in said opening to form a fluid tight connection 60 thereat.

4. In a device of the kind described, a plate having an opening therethrough, a shoulder formed in the walls of said opening intermediate its ends, the opening being larger at one side of said shoulder than at the opposite side thereof and a tube extending into said opening and through the smaller portion thereof, in combination with a longitudinally flexible member inclosing a 70 portion of said tube and having one end permanently attached thereto and substantially constituting therewith a unitary structure, a flange at the opposite end of said member positioned in said opening and adapted to 75 coöperate with said shoulder and means extending into the larger portion of said opening for clamping said flange to said shoulder to form a fluid tight connection between 80 said plate and tube.

5. In a device of the kind described, a plate having an opening therethrough, a shoulder formed in the walls of said opening intermediate the ends, the opening being larger at one side of said shoulder than 85 at the opposite side thereof and a tube extending into said opening and through the smaller portion thereof, in combination with a longitudinally flexible member inclosing a portion of said tube and having one of its 90 ends permanently attached to the tube adjacent the end thereof, said member having a flange at its opposite end positioned in said opening and adapted to coöperate with said shoulder and a separable annular member extending into the larger portion of said opening and engaging the walls thereof to lock said member in position for clamping said flange to said shoulder to form a fluid 95 tight connection between said plate and tube. 100

In testimony whereof I have hereunto signed my name in the presence of two subscribing witnesses.

FREDERICK SARGENT.
